UNITED STATES PATENT OFFICE.

ELMER C. BEECHER, OF WAKEMAN, OHIO, ASSIGNOR OF ONE-THIRD TO HERBERT C. BEECHER, OF SAN FRANCISCO, CALIFORNIA, AND ONE-THIRD TO RAYMOND L. BEECHER, OF DETROIT, MICHIGAN.

AUTO TRAFFIC SIGNAL.

Application filed October 7, 1925. Serial No. 61,057.

The present invention relates to rear lights for motor vehicles and aims to provide a rear lamp construction which will combine the stop, right and left signal lamps and usual 5 tail-light in a single casing.

Another object of the invention is to provide a device of this character including a cover having a central cut away portion and enlarged cut away portions at the ends of 10 the central cut away portion, defining arrow heads, novel means being provided for deflecting light ray from lamps positioned behind the cover to illuminate the central portion and either of the arrow heads, displaying 15 complete arrows.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, may be made within the scope of what is claimed, without 25 departing from the spirit of the invention.

Referring to the drawing:

Figure 1 is an elevational view of a lamp casing constructed in accordance with the invention.

30 Figure 2 is an elevational view of the lamp casing, the cover thereof having been removed.

Figure 3 is a sectional view taken on line 3-3 of Figure 1.

35 Referring to the drawing in detail, the lamp casing is box-like in formation and is provided with lateral offset portions 5 defining arrow heads, while the upper portion of the casing is more or less elongated to 40 provide a relatively long compartment 6.

Arranged within the casing are lateral partitioning members 7 and 8 respectively which are disposed adjacent to the lateral offset portions 5 and have downwardly and 45 outwardly extended portions 9 that engage the side wall of the casing as clearly shown by Figure 2 of the drawing, to the end that the upper portion of the casing at these points will be protected from the light rays 50 of the lamps positioned within the casing.

Walls 10 and 11 have connection with the walls 7 and 8 and are arranged in spaced relation with each other to define a central compartment 12 in which the deflecting

member 13 is positioned, which deflecting member has its central portion spaced from the lens, to be hereinafter more fully described, so that light rays from the lamps may be directed laterally.

55 The walls 7 and 8 are formed with cut out portions curved to conform to the curvature of an electric lamp, the walls being arranged within the casing in such a way that the electric lamps supported within the cut out portions are arranged in such a way that 60 the light rays projected therefrom, will be divided in a manner as shown by Figure 3 of the drawing.

65 Thus it will be seen that when the lamp at the left of the casing as shown by Figure 70 3 is illuminated, the central portion of the cover will be illuminated and the arrow head at the left will be illuminated defining a complete arrow. Should the lamp 14 at the 75 right hand side of the casing in Figure 3 be illuminated, it will be seen that the arrow head at the right side of the casing will be illuminated as well as the central portion of the cover, defining a complete arrow, 80 while the arrow head at the opposite side of the casing remains dark.

85 The cover is indicated at 17 and is provided with suitable openings to receive securing screws that also pass through flanges 17' extending inwardly from the casing. Secured between the flanges and cover is a support 15 on which the lens 16 is positioned. Thus it will be seen that due to this construction, the transparent covering or 90 lens which is supplied with suitable indicating characters indicating "stop", "danger" and "right" and "left", may be readily secured in position.

95 The bulbs which are positioned in the casing are controlled independently by switches located adjacent to the operator's seat. Supported at the rear of the body portion is a support for the lamps and wires connected therewith.

100 At the rear of the body portion or casing is a supporting plate indicated at 19 which is formed with a central opening through which the wires 20 pass, which wires lead to the lamps illuminating the body portion.

105 Bolts 21 secure the plate 19 to the body portion and hold the plate 19 in suitable spaced relation with the body portion.

I claim:-

A lamp casing including a body portion, a pair of parallel spaced partitioning members within the body portion defining a plurality of lamp compartments, end partitioning members spaced from the sides of the casing and having connection with the ends of the first mentioned partitioning members, the last mentioned partitioning members having cut out portions formed in the lower edges thereof and adapted to accom-

modate electric lamps, a deflecting member of a width to fit between the parallel partitioning members, said deflecting member being bent outwardly at a point intermediate its ends to provide lateral inclined deflecting surfaces, and a cover for the casing. 15

In testimony that I claim the foregoing as my own, I have hereto affixed my signature.

ELMER C. BEECHER.
